UNITED STATES PATENT OFFICE.

ERNEST OLDENBUSCH, OF BROOKLYN, NEW YORK.

CIGARETTE-CASE.

1,288,150.

Specification of Letters Patent. Patented Dec. 17, 1918.

Application filed May 31, 1918. Serial No. 237,427.

To all whom it may concern:

Be it known that I, ERNEST OLDENBUSCH, a citizen of the United States, and a resident of the city of New York, borough of Brooklyn, in the county of Kings and State of New York, have invented a new and Improved Cigarette-Case, of which the following is a full, clear, and exact description.

This invention relates to cigarette cases of the thin metal shell type for holding a single layer of cigarettes.

The invention has for its general objects to provide a case of improved construction which permits of the easy and convenient placing of the cigarettes therein without danger of the cigarettes being broken, the case being composed of half sections which are hinged together at the bottom so that the case can be completely opened for placing the cigarettes therein, one section of the case having seats arranged in a line so that the cigarettes can be placed in the seats and held thereby in proper spaced relation when the case is closed.

25 The upper part of each half or section of the case is a hinged closing member held by a suitable locking means and each acted on by a spring, so that when the locking means is released the upper part of the case will open, with the cigarettes projecting therefrom in a convenient manner to be removed.

For a more complete understanding of the invention reference is to be had to the following description and claims taken in connection with the accompanying drawing, wherein similar characters of reference indicate corresponding parts in all the views, and in which

40 Figure 1 is a perspective view of the cigarette case with the cover members opened;

Fig. 2 is a perspective view showing the case entirely open for the reception of the cigarettes;

Fig. 3 is a vertical section of the case completely closed;

Fig. 4 is a perspective view of a cigarette case showing a modified construction;

50 Fig. 5 is an enlarged vertical view of the construction shown in Fig. 4; and

Fig. 6 is a horizontal section on the line 6—6, Fig. 5, with cigarettes in the case.

Referring to the drawing, A designates 55 the cigarette case, which is composed of two substantially similar sections 1 and 2 made

of metal or other suitable material, each section being a rectangular shallow pan-like piece, and the two sections are connected together by a hinge 3 at the bottom, so that when the sections are closed together they form a hollow casing for holding a single row or layer of cigarettes in parallel relation to each other. Each section has an upper closing or cover member 4 adapted to swing 65 on a hinge 5, and at the hinge is a spring 6 which is normally under tension to throw the members 4 to a position at right-angles to the body of the casing, as shown in Fig. 1. A latch 7 is carried by a spring 8 which is 70 fastened at 9 on one member 4 in such position that the latch will engage a catch 10 on the other member 4. On the latch is a lug 11 which projects through an opening 12 so that by pressing inwardly on the lug 75 the latch 7 is removed from the catch 10, so that the two members 4 will spring open from the closed position shown in Fig. 3 to the open position shown in Fig. 1.

Any suitable means may be employed to 80 hold the sections 1 and 2 together in closed position. In the present instance the section 1 has a bar 13 which extends at right-angles to the hinge 3 and one edge is provided with a notch 14 in which is a catch lug 15 that is 85 adapted to enter and interlock with an aperture 16 in the section 2 to thereby releasably hold the body of the casing closed.

To hold the cigarettes parallel and in proper order while they are being arranged 90 in the open case, as in Fig. 2, the section 2 has a row of corrugations forming seats 17 formed by stamping the metal in a suitable die, and each cigarette is placed to engage in a seat 17, which is concave to correspond 95 to the curvature of the cigarette.

In the modification shown in Fig. 4 the seats for holding the individual cigarettes are formed in an extra plate 18 which is attached to the section 2^a by hinge ears 18^a 100 which engage the pintle 5^a of the hinge 5, and the plate 18 is provided with parallel corrugations so that each corrugation forms a seat for a cigarette. The advantage of this construction is that the outside surface 105 of the section 2 is not disfigured, as shown in Fig. 1.

Another modified feature is the provision of a concealed catch 19 which is adapted to engage in a recess 20 formed in the edge of 110 the bar 13^a. The interengaging portions 19 and 20 lock and unlock automatically by

pressure applied to the two sections 1^a and 2^a of the case, there being enough spring at the hinge between the sections to allow the parts 19 and 20 to engage and disengage.

5 The member or bar 13 or 13^a projects upwardly above the hinges 5, so that the closing members 4 of the case are prevented from swinging to one side or the other of their normal closed position.

10 From the foregoing description taken in connection with the accompanying drawing, the advantages of the construction and method of operation will be readily understood by those skilled in the art to which the invention appertains, and while I have described the principle of operation, together with the article which I now consider to be the best embodiment thereof, I desire to have it understood that the article shown 15 is merely illustrative and that such changes may be made when desired as fall within the scope of the appended claims.

Having thus described my invention, I claim as new and desire to secure by Letters 20 Patent:

1. A cigarette case comprising a body composed of halves hingedly connected together and adapted to hold a plurality of cigarettes with projecting ends, and a cover section hingedly connected with each of the said halves of the body, and the cover sections being adapted to open while the said halves remain in closed position.

2. A cigarette case divided into two parts 25 hingedly connected together, each being composed of two sections hingedly connected together, and separate means for holding

the corresponding sections of the parts in closed relation.

3. A cigarette case comprising a body 40 composed of two substantially similar sections hingedly connected at their bottom edges, complementary catch means on the two sections for releasably holding the same in closed position, spring-opened cover members attached to the upper edges of the said body sections, and catch means for holding the cover members in closed position.

4. A cigarette case of the class described comprising a body composed of two substantially similar sections hinged together, one section having a plurality of seats for the individual cigarettes, catch means for holding the sections in closed position, spring-opened closing members attached to the said sections, and means for holding the said members in closed position.

5. A case for cigarettes or the like, comprising a pair of hingedly connected sections, a closing member hingedly connected 60 with each section, and a seat plate connected with one of the sections at the hinge between the latter and the associated closing member.

6. A case for cigarettes or the like, comprising a pair of hingedly connected body sections, cover members hingedly connected with the sections, and a bar attached to one of the body sections and extending upwardly from between the sections to form a support for the cover members when in closed position.

ERNEST OLDENBUSCH.

Copies of this patent may be obtained for five cents each, by addressing the "Commissioner of Patents, Washington, D. C."
